UNITED STATES PATENT OFFICE

112,590

DESIGN FOR A KNIFE

John E. MacPherson, Franklinville, N. Y., assignor to The Ontario Knife Company, Franklinville, N. Y.

Application July 6, 1938, Serial No. 78,307

Term of patent 14 years

To all whom it may concern:

Be it known that I, John E. MacPherson, a citizen of the United States, residing at Franklinville, county of Cattaraugus, and State of New York, have invented a new, original, and ornamental Design for a Knife, of which the following is a specification, reference being had to the accompanying drawing, forming part thereof.

The figure is a face view of a knife showing my new design.

The dominant feature of my new design resides in the ornamentation applied to a blade as shown in full lines.

The knife blade is of conventional thickness and both sides of the blade are substantially alike.

I claim:

The ornamental design for a knife, as shown and described.

JOHN E. MACPHERSON.
